UNITED STATES PATENT OFFICE.

ALFRED H. HUMPHREY, OF NEW YORK, N. Y.

GAS-LAMP.

No. 861,182.

Specification of Letters Patent.

Patented July 23, 1907.

Original application filed June 22, 1906, Serial No. 322,891. Divided and this application filed June 6, 1907. Serial No. 377,652.

To all whom it may concern:

Be it known that I, ALFRED H. HUMPHREY, a citizen of the United States, residing at the city of New York, county of New York, and State of New York, 5 have invented certain new and useful Improvements in Gas-Lamps, of which the following is a specification.

This invention relates to improvements in gas lamps.

My invention relates particularly to improvements in valves for gas lamps, and is especially designed by 10 me for use in connection with my improved gas lamp shown and described in my application for Letters Patent filed June 22, 1906, Serial No. 322,891, this application being a division thereof, although it is adapted and desirable for use in various other relations.

15 The main object of this invention is to provide in a gas lamp an improved valve for controlling the main burners and the pilot burner.

Further objects, and objects relating to structural details, will definitely appear from the detailed description 20 to follow.

I accomplish the objects of my invention by the devices and means described in the following specification.

The invention is clearly defined and pointed out in 25 the claims.

A structure embodying the features of my invention is clearly illustrated in the accompanying drawing, forming a part of this specification, in which:

Figure 1 is a view, partially in vertical section, of a 30 gas lamp embodying the features of my invention. Fig. 2 is an enlarged detail elevation of the valve mechanism taken looking from the left of Fig. 1. Fig. 3 is an enlarged section through the valve taken on a line corresponding to line 3-3 of Fig. 2, the valve for the main 35 burner being open and the pilot burner valve being closed. Fig. 4 is a detail section showing the pilot burner valve in its open or flashing position. Fig. 5 is an enlarged detail section taken on a line corresponding to line 5-5 of Fig. 1, showing structural details of the 40 valve lever.

In the drawings, the sectional views are taken looking in the direction of the little arrows at the ends of the section lines, and similar letters of reference refer to similar parts throughout the several views.

45 Referring to the drawings, 1 represents a gas delivery pipe which is provided with a coupling 2 from which depends the gas delivery pipe extension 3. At the lower end of this extension 3 is the valve casing 4. The delivery pipe 5 connects the valve casing to the gas 50 delivery ring 6, the parts being the same in a general structure as described in my application for patent above referred to.

The chimney 7 is provided with an outwardly-projecting flange 8 having a downwardly-projecting rim 9 55 at the outer edge thereof. The main burner 10 is ar-

ranged through the flange 8 and connected to the gas delivery ring. The mantle 11 is suspended from the mantle holder 12. The chimney is preferably supported from the gas delivery pipe 3, the clip or strap 13 being arranged to embrace the pipe and being secured thereto by means of suitable collars, as 14. An outer casing, as 15, is provided, above which is a reflector plate 16, the reflector plate being supported on the supply pipe, as appears from the drawing.

The globe-supporting band 17 for the globe 20 is pivotally secured to the depending hinge member 8 on the valve casing by means of a suitable pivot 19. The casing 15 is preferably supported by resting upon the casing band 21, which is mounted on the chimney flange 8. These parts are substantially the same as 60 those described in my application for patent above referred to, but it will be readily understood that my improved valve is adapted to use in various other relations, and I show the same in this connection merely to show its utility and application.

The valve casing 4 is provided with the inlet passage 22, to which the gas delivery pipe 3 is connected to deliver and the discharge passage 23, to which the delivery pipe 5 is connected. These passages are connected by the passage 24, which is controlled by the valve 25. 65 This valve is a rotary valve and is provided with two ports 26, arranged to be alternately brought into register with the passage 24 for opening the valve as it is rotated. On the stem 27 of the valve 25 is pivoted the valve operating lever 28. This lever is preferably 70 made up of three pieces, 29, 29 and 30, the part or piece 30 being riveted between the pieces 29, whereby they are held properly spaced. Between these pieces 29 I arrange the ratchet 33, which is secured to the valve stem. The valve lever is provided with a pawl 31 75 adapted to engage the ratchet 33, the pawl being arranged between the lever parts 29. A spring 34 is provided for holding the pawl in its engaging position.

The ratchet is provided with four teeth, it being 80 secured on the stem in such a position that one motion of the lever will open the valve and the next close it. The valve stem is provided with an index 41, which is 85 designed to indicate whether the valve is in its open or closed position, it being shown by full lines in its open position in Fig. 2, and by dotted lines in its closed position. A spring dog, 35, adapted to engage the ratchet and prevent rearward movement thereof, is provided, the dog being secured to the valve casing and projecting outwardly therefrom, as clearly appears 90 in Fig. 3.

The valve lever is provided with a rearwardly-projecting arm 39, which is adapted to engage the pin 38 and thereby limit the stroke of the lever. This pin also serves as a support for the return spring 40, one 95

end of which is secured thereto, the other end being secured to the outer end of the valve lever, as clearly appears from the drawing.

The valve lever is provided with a projecting pin 50, 5 which is adapted to engage the lever 42 of the pilot valve on the stroke of the main valve lever. The main burner valve lever is adapted to engage the pilot valve lever when it has partially completed its stroke, thereby opening the pilot valve after the main burner 10 valve is partially open. The pilot valve 43 is threaded into a cup-like valve casing 45, the casing being in turn threaded into the main valve casing 4. This pilot valve casing 45 is provided with a port 46 through its inner end and a passage 47 through one side thereof, to 15 which the pilot burner 44 is connected.

The valve 43 is provided with a port 51, which is always open to supply sufficient gas to maintain the pilot. The delivery of the gas through this passage is controlled by means of the screw valve 49, which is threaded 20 into the valve 43 from its outer end. This enables the accurate adjustment of the port to regulate the flow of gas to the pilot. When the pilot valve lever 42 is actuated, the valve is drawn from its seat on the inner end of the casing 45, allowing the gas to pass to the pilot for 25 flashing the same. As soon, however, as the main valve lever 28 is released, it is returned to its initial position, as stated, by the spring 40 and the pilot valve is closed by means of the spring 52, which is connected thereto and the pin 38 on the valve casing 4. Thus arranged, the pilot valve is automatically closed when the main burner valve lever is released. The valve levers 28 and 42 are so arranged that the main valve is opened or partially opened before the pilot is flashed, allowing the gas to drive the air from the burners and 35 the gas delivery pipes beyond the valves. When it is desired to cut off the gas or turn out the light, it is only necessary to again pull on the operating chain, as 53, and the valves are closed.

My improved valve is very effective for the purpose 40 and is, at the same time, comparatively simple and economical to produce. I have illustrated and described the same in detail in the form preferred by me on account of structural economy and convenience in use. I am, however, aware that it is capable of considerable variation in structural details without departing from my invention, and I desire to be understood as claiming the same specifically, as illustrated, as 45 well as broadly.

Having thus described my invention, what I claim 50 as new and desire to secure by Letters Patent, is:

1. In a gas lamp, the combination of a main burner; a pilot light; a valve casing having suitable passages therein; a rotary valve for said main burner having oppositely arranged ports therein; a ratchet on said main burner valve; a lever pivoted on said main burner valve, having a pawl adapted to engage said ratchet; a spring dog for said ratchet; a stop for said lever; a spring for returning said lever to its initial position; an indicator carried by said main burner valve; a cup-like pilot-light valve casing 55 having ports in the end thereof, threaded into said main valve casing, said pilot-light valve casing having a passage connecting the same to said pilot-light, a hollow pilot light valve having a port in the side thereof, threaded into said pilot valve casing and arranged to embrace the said 60 port in the inner end thereof, the end of said casing forming a seat for said pilot valve, a screw valve for adjusting said port in said pilot valve; and a lever on said pilot valve, adapted to be engaged by the lever on said main 65 valve, adapted to be engaged by the lever on said main

burner valve toward the completion of its stroke; and a spring for closing said pilot valve, co-acting for the purpose specified. 70

2. In a gas lamp, the combination of a main burner; a pilot light; a valve casing having suitable passages therein; a rotary valve for said main burner having oppositely arranged ports therein; a ratchet on said main burner valve; a lever pivoted on said main burner valve, having a pawl adapted to engage said ratchet; a spring dog for said ratchet; a stop for said lever; a spring for returning said lever to its initial position; a cup-like pilot-light valve casing having a port in the end thereof threaded into said main valve casing, said pilot-light valve casing having a passage connecting the same to said pilot light, a hollow pilot light valve having a port in the side thereof threaded into said pilot valve casing and arranged to engage the said port in the inner end thereof, the end of said casing forming a seat for said pilot valve, a screw valve for adjusting said port in said pilot valve; and a lever on said pilot valve, adapted to be engaged by the lever on said main burner valve toward the completion of its stroke; and a spring for closing said pilot valve, co-acting for the purpose specified. 80

3. In a gas lamp, the combination of a main burner; a pilot light; a valve casing having suitable passages therein; a rotary valve for said main burner having oppositely arranged ports therein; a ratchet on said main burner valve; a lever pivoted on said main burner valve, having a pawl adapted to engage said ratchet; a spring for returning said lever to its initial position; a cup-like pilot-light valve casing having a port in the end thereof threaded into said main valve casing, said pilot-light valve casing having a passage connecting the same to said pilot light, a hollow pilot light valve having a port in the side thereof threaded into said pilot valve casing and arranged to embrace the said port in the end thereof, the end of said casing forming a seat for said pilot valve, a screw valve for adjusting the said port in said pilot valve; and a lever on said pilot valve, adapted to be engaged by the lever on said main burner valve, toward the completion of its stroke; and a spring for closing said pilot valve, co-acting for the purpose specified. 90

4. In a gas lamp, the combination of a main burner; a pilot light; a valve casing having suitable passages therein; a rotary valve for said main burner, having oppositely arranged ports therein; a ratchet on said main burner valve; a lever pivoted on said main burner valve, having a pawl adapted to engage said ratchet; a spring for returning said lever to its initial position; a cup-like pilot-light valve casing having a port in the end thereof threaded into said main valve casing, said pilot-light valve casing having a passage connecting the same to said pilot light, a hollow pilot-light valve having a port in the side thereof threaded into said pilot valve casing and arranged to engage the said port in the inner end thereof, the end of said casing forming a seat for said pilot valve; and a lever on said pilot valve, adapted to be engaged by the lever on said main burner valve toward the completion of its stroke; and a spring for closing said pilot valve, co-acting for the purpose specified. 100

5. In a gas lamp, the combination of a main burner; a pilot light; a valve casing having suitable passages therein; a rotary valve for said main burner, having oppositely arranged ports therein; a ratchet on said main burner valve; a lever pivoted on said main burner valve, having a pawl adapted to engage said ratchet; a spring for returning said lever to its initial position; a cup-like pilot-light valve casing having a port in the end thereof threaded into said main valve casing, said pilot-light valve casing having a passage connecting the same to said pilot light, a hollow pilot-light valve having a port in the side thereof, threaded into said pilot valve casing and arranged to embrace the said port in the end thereof, the end of said casing forming a seat for said pilot valve; and a lever on said pilot valve, adapted to be engaged by the lever on said main burner valve, toward the completion of its stroke; and a spring for closing said pilot valve, co-acting for the purpose specified. 110

6. In a gas lamp, the combination of a main burner; a pilot light; a valve casing having suitable passages there-

- in; a rotary valve for said main burner; a ratchet on said main burner valve; a lever pivoted on said main burner valve, having a pawl adapted to engage said ratchet; a spring dog for said ratchet; a stop for said lever; a spring 5 for returning said lever to its initial position; an indicator carried by said main burner valve; a pilot light valve; a lever for said pilot valve, adapted to be engaged by the lever on said main burner valve toward the completion of its stroke; and a spring for closing said pilot valve, 10 co-acting for the purpose specified.
7. In a gas lamp, the combination of a main burner; a pilot light; a valve casing having suitable passages therein; a rotary valve for said main burner; a ratchet on said main burner valve; a lever pivoted on said main burner valve, having a pawl adapted to engage said ratchet; a spring 15 for returning said lever to its initial position; a pilot light valve; a lever for said pilot valve, adapted to be engaged by the lever on said main burner valve toward the completion of its stroke; and a spring for closing said pilot valve, 20 co-acting for the purpose specified.
8. In a gas lamp, the combination of a main burner; a pilot light; a valve casing having suitable passages therein; a rotary valve for said main burner; a ratchet on said main burner valve; a lever pivoted on said main burner valve, having a pawl adapted to engage said ratchet; a stop 25 for said lever; a spring for returning said lever to its initial position; a pilot light valve; a lever for said pilot valve adapted to be engaged by the lever on said
- main burner valve toward the completion of its stroke; 30 and a spring for closing said pilot valve, co-acting for the purpose specified.
9. In a gas lamp, the combination of a main burner; a pilot light; a valve casing having suitable passages therein; a rotary valve for said main burner; a ratchet on said main burner valve; a pivoted lever having a pawl adapted to engage said ratchet; a stop for said lever; a spring for returning said lever to its initial position; a pilot light 35 valve; a lever for said pilot light valve adapted to be engaged and actuated by the lever on said main burner valve 40 during its stroke, and a spring for closing said pilot valve when released, co-acting for the purpose specified.
10. In a gas lamp, the combination with a flash pilot light of a valve casing having a port in the end thereof, said casing having a passage connecting the same to said 45 pilot light; a hollow valve having a port in the side, threaded into said casing and arranged to embrace said port therein, the inner end of said casing forming a seat for said valve; and a screw valve arranged longitudinally in said hollow valve for adjusting the said port in the side 50 thereof, for the purpose specified.

In witness whereof, I have hereunto set my hand and seal in the presence of two witnesses.

ALFRED H. HUMPHREY. [L. S.]
